UNITED STATES PATENT OFFICE.

HERBERT TALLEY, OF JOPLIN, MISSOURI, ASSIGNOR TO INDEPENDENT POWDER COMPANY, OF JOPLIN, MISSOURI, A CORPORATION OF MISSOURI.

SHELL FILLING AND LOADING MACHINE.

1,083,771.

Specification of Letters Patent.

Patented Jan. 6, 1914.

Original application filed April 19, 1912, Serial No. 691,825. Divided and this application filed August 13, 1912. Serial No. 714,859.

To all whom it may concern:

Be it known that I, HERBERT TALLEY, a citizen of the United States, residing at Joplin, county of Jasper, and State of Missouri, have invented certain new and useful Improvements in Shell Filling and Loading Machines, of which the following is a specification.

This invention relates to shell filling and loading machines.

The present application is a division of my application on shell filling and closing machines, Serial No. 691,825, filed April 19, 1912.

The present invention has for its objects the provision of novel means for automatically loading material, particularly plastic explosives such as gelatin dynamite, into paper cartridges or shells by which safe guards will be provided against undue or too rapidly applied pressure in forcing the explosive into the shells and also providing for the relatively rapid return of the parts to normal position after the filling operation has been consummated.

In carrying out the invention, I provide novel motive fluid pressure operated means, and novel controlling mechanism therefor, whereby the parts are placed in loading position by a more or less gradual movement as contradistinguished from a quick or abrupt movement, and, further, the extrusion or forcing of the explosive into the shells is initiated and continued in an even and regular, but not abrupt, manner, whereby too sudden or undue pressure on the explosive is prevented during loading and relatively quick return of the parts to normal position is insured, such mechanism preferably embracing, first, a bodily movable feeder or loader, means for operating the feeder or loader independent of its bodily movement, and means for moving it into or out of loading position; second, controlling and master or operated valves adapted to coöperate in a new manner to regulate and control the access to and relief of motive fluid pressure from the loading mechanism; third, a controlling valve and means whereby it is automatically operated by the movement of the loading mechanism; fourth, a relief valve and means whereby it is automatically operated by the movement of the loading mechanism, whereby the density of the ex-

plosive loaded into the shells is regulated; 55 fifth, a novel controlling system for the motive fluid pressure whereby the loading mechanism is advanced and set into operation in a relatively slow manner but without undue delay in operation and is relatively quickly returned after the loading operation has been carried out; and, further, in various features, mechanisms, pipe connections and valves arranged to carry out the objects of the invention as will more 60 fully appear hereinafter.

In the accompanying drawings: Figure 1 is an elevation; Fig. 2, an elevation taken at the left of Fig. 1, certain parts being in section and broken away; Fig. 3, a detail view of the pilot and master valves and their connections; Fig. 4, a diagrammatic view of the different mechanisms and the fluid pressure operating and controlling system therefor, and Fig. 5, a detail view of a certain locking device.

The frame consists mainly of uprights 1 and a yoke 2. Slidable on the uprights 1 is a carriage 3, the lower part of which carries a feed hopper 4 which has an extended 80 or elongated mouth 5 so that the explosive can be fed thereto and a quantity be ready for admission to the hopper as the piston makes its successive strokes. Attached to the bottom of the hopper 4 are nipples or 85 nozzles 6. These are preferably carried by a single removable end or head which is detachably connected to the lower end of the hopper. These nipples are adapted for insertion into the paper shells which are commonly employed for containing the gelatin dynamite which the machine is adapted to load. The nipples 6 are grouped in as great 90 a number as desired, the number corresponding to the number of shells adapted to be 95 held by the shell holder or shuttle and to the position of the shells therein.

The cylinder 7 is carried by carriage 3. Operable therein is a piston 8 whose rod or plunger 9 carries a forcing piston or plunger 10 adapted to operate in the hopper 4 and to fit it. As the piston or plunger 10 advances in the hopper 4, it forces the plastic explosive gelatin dynamite out through the nipples or nozzles 6 and into the shells. 100 The piston or plunger rod 9 carries a cross-head 11 which is slidable on the sleeves of carriage 3, the said cross-head and piston

being adapted to move in relation to the carriage independently of the movement of the carriage up or down on the uprights 1.

To assist the motive fluid pressure operating and controlling mechanisms herein-after described in giving an even and regular rather than an abrupt movement to the piston 8, particularly in its downward stroke when loading the shells, there are 10 provided cylinders 12 containing oil in which pistons 13 are adapted to move, said pistons being connected by rods 14 to the cross-head 11. The pistons 13 have a loose fit in the cylinders 12 so that the oil contained in the cylinders 12 may gradually flow from one side of the piston to the other, this arrangement constituting an oil check whichever way the piston 8 is moving. To equalize the flow of the oil and the resistance 15 of the pistons 13, the cylinders 12 may be connected by a pipe 15.

Carried by the yoke 2, is an operating cylinder 16 in which moves a piston 17 whose piston rod 18 is connected to the carriage 3 in any suitable manner, the piston rods 9 and 18 being preferably in alinement. Oil checks embodying cylinders 19, pistons 20 and rods 21 connecting said pistons 20 to the carriage 3, serve as an oil check to prevent too abrupt upward or downward movements of the carriage 3 by the piston 17 and its rod 18. The piston 17 is adapted to move the carriage 3 downwardly to position the nipples 6 in the shells prior to the extrusion of the explosive gelatin from the hopper 4 by the piston 10 which is operated by piston 8.

Preferably the carriage 3 and all parts carried thereby are counterpoised, so as to 40 minimize the air or other motive fluid pressure required to operate them. Such counterweighting may be conveniently accomplished by providing a shaft 22 secured to or mounted on the uprights 1 and secured 45 to or mounted on said shaft are sheaves 23 over which run cables 24 connected to the carriage 3 and provided with a suitable weight 25.

Rotatably mounted in or on the uprights 50 1 is a shell carrier 26 which is adapted for rotation to move the shell holders or shuttles 27 to their different positions. Suitable means may be provided to catch the closed and completed shells dumped from the lowest 55 shuttle 27, but I prefer to employ a rotatable table 28 which may be conveniently mounted on one of the uprights 1 for the reception of succeeding batches of filled and closed shells and the even distribution over 60 its surface of the shells so that they may be conveniently and regularly removed by hand.

The mechanisms now to be described may be mounted in any preferred position but, 65 preferably, the trip mechanism and the pilot

valve are disposed on the frame 1 or yoke 2 in position for convenient tripping and manual control.

At 107 is disclosed a four-way pilot valve which controls the operation of the entire 70 machine. Air pressure from any suitable source is supplied to the valve casing by pipe 108; 109 is an exhaust branch for the valve.

At 110 is shown a controlling cylinder, 75 one end of which has a pipe connection 111 with the four-way valve 107 and the opposite end a pipe connection 112 with said valve 107. A lever 113 is carried by the valve and adapted for operating it, said lever being pulled in one direction by a spring 114 and adapted to be pulled in the opposite direction by hand or through the intervention of a cord or chain 115 if disposed out of convenient reach of the operator. The 80 spring 114 maintains the valve 107 in such position that air will exhaust from cylinder 110 through pipes 112 and 109 and will be admitted from supply pipe 108 to pipe 111.

At 116 is a four-way master valve which 85 is operated by a piston 117 in cylinder 110 and a piston rod 118 connected to said valve. A suitable dash-pot 119 is connected to piston rod 118. When the parts are in the position set forth, the supply of air through 90 the pipe 111 maintains piston 117 in such position that the four-way master valve 116 is so positioned that all the mechanisms are retracted so as to be ready to perform their 95 respective functions.

At 120 is a latch which has an offset end 121 adapted to lock the end 122 of lever 113 (Fig. 5) when said lever is raised by pulling on the cord 115 against the action of spring 114. The latch 120 is maintained in position after locking lever 113 by a spring 123. The latch 120 may be moved in opposition to spring 123 to release lever 113 if engaged therewith by a cord 124. The carriage 3 carries a trip 125 which is adapted to engage 100 the latch 120 on the return of the carriage to its raised position after the shells in the shuttle have been filled, and the lever 113 being engaged with the part 121 during the previous operation of the machine, is thereupon released so that the lever 113 resumes 105 its normal position, placing the different cylinders in communication with their exhausts.

Referring to diagrammatic Fig. 4, the arrangement of the cylinders, their piping, valves and controlling mechanisms are 110 therein disclosed. The spaces above the pistons 8 and 17 are connected to master valve 116 by pipes 126, the valve placing these 115 pipes in communication with the exhaust 128 of the master valve when the parts are in normal position. The spaces below pistons 8 and 17 have pipe connections 129 and 130, both communicating with the pipe 131 which 125

leads to the master valve 116. At a suitable point in the pipe 126 is a pressure checking valve 132 of any preferred type which momentarily cuts down the pressure entering pipes 126 from the feed pipe 108 so that a too sudden application of pressure to the pistons 8 and 17 will be prevented as it would result in too abrupt descent of the carriage 3 and too abrupt forcing of the explosive into the shells. In the pipe 131 there is introduced a check valve 133 which permits a slow exhaust from the cylinders 7 and 16 below the pistons 8 and 17 thereof when the air is exhausting as the pistons are descending, or, a rapid supply of pressure when it is introduced via pipe 129 into the lower end of said cylinder 16 to raise the piston therein, thus providing for a quick lifting action of the carriage 3. In the pipe 130 there is provided a pressure reducing valve 134 which, while suitably reducing the pressure, permits a comparatively quick introduction of pressure through pipe 130 below the piston 8 so that it may be comparatively quickly returned upwardly after the shells have been loaded. A valve 135 in a by-pass pipe 136 permits only an exhaust of the pressure from below the piston 8 when the latter is descending to force the explosive into the shells. This valve, by checking the exhaust from below piston 8 to a suitable extent, prevents too rapid descent of the piston 8 when the shells are being filled.

The pipe 126 is provided with a three-way valve 155 which controls said pipe and also an exhaust pipe 156 having a relief valve 157. The valve 157 may be of any preferred type which is adapted to be set to open at any predetermined pressure. The valve 155 is automatically operated by a rod 158 having stops 159 and 160 and it is arranged so that a bracket 161 on the carriage 3 is adapted to engage the stops 159 and 160 at different points. Pressure having been admitted into the pipe 126, the carriage 3 is forced downwardly by piston 17 to position the nipples 6 in the shells. The piston 8 is also forced downwardly by pressure in pipe 126 so that the plunger 10 presses the explosive into the shells. At the proper point of movement, the bracket 161 strikes the stop 160, thereupon turning the valve 155 to release the pressure from above the piston 17 into the pipe 156. The valve 157, according to the pressure at which it has been set to let off, determines the density of the explosive gelatin or other material forced into the shells because the carriage 3 will remain down until it is forced upwardly by the reactive pressure of the explosive in the shells, as the shells are filled by the plunger 10. Eventually the lift of the carriage caused by the reactive pressure of the explosive on the plunger 10 due to the filling of the shells causes the trip 125 to strike the latch 120

and press it aside, thereby releasing the lever 113 whose spring 114 immediately snaps it to its normal position, whereupon the air pressure from pipe 108 passes through the pilot valve 107 into pipe 111, resulting in the master valve 116 being reversed. The reversal of the master valve causes the air to pass into pipes 129 and 131 and also into pipe 130. The carriage is thereupon raised to its full height by the admission of air under the piston 17 and the bracket 161 strikes the stop 159, thereby returning the three-way valve 155 to its normal position where it is adapted to permit pressure, when entering pipe 126, to pass to the cylinder 16 on the next operation of the machine. The access of pressure through pipe 130, forces the piston 8 upwardly. This movement is a substantially quick return movement.

On pulling the cord 115 or moving the lever 113 to latch it at 121, operations such as previously set forth ensue. The master valve 116 is reversed, the air is admitted into pipes 126 at checked pressure, whereby the carriage is forced downward by piston 17 to position the nipples in the empty shells. The piston 8 also forces the plunger 10 into the hopper 4, forcing out the explosive into the shells.

The parts being in the positions indicated, the rising of the carriage due to the reactive pressure of the explosive gelatin on the nipples, the hopper, and hence the carriage causes the carriage to retreat, the stop 159 being struck and the valve 155 turned to normal position ready to admit pressure through pipe 126 to cylinder 16; also, the trip 125 engages the latch 120 and releases the lever 113, whereupon the return of the parts to normal position takes place, as previously set forth.

Having thus described my invention, what I claim as new and desire to secure by Letters Patent, is:

1. In a shell loading machine, the combination with a shell holder, of a bodily movable operable feeding means adapted for loading the shells in the holder, means for operating said feeding means independent of its bodily movement aforesaid, and means for bodily moving the feeding means to position said means for the performance of the loading operation.

2. In a shell loading machine, the combination with a shell holder, of a movably mounted feeding hopper, a piston movable in said hopper independently of the movement of the hopper itself, means for moving the hopper, and means for operating the piston, whereby the hopper may be positioned for the feeding of the material to the shells and for the material to be forced from the hopper into the shells.

3. In a shell loading machine, the combination with a shell holder, of a fluid pres-

- sure operated motor, operable feeding means mounted for bodily movement of said motor, and another fluid pressure operated motor adapted for causing the feeding means aforesaid to carry on the feeding operation.
4. In a shell loading machine, the combination with a shell holder, of a carriage, a feeding hopper carried thereby, a motive fluid pressure cylinder and piston carried by the carriage, an extruding plunger operated thereby which is adapted to operate in the feeding hopper, and a piston and cylinder for moving the carriage.
5. In a shell loading machine, the combination with fluid pressure operated feeding means, of a controlling valve for the fluid pressure therefor, and means for automatically operating said valve by the feeding means.
6. In a shell loading machine, the combination with movably mounted feeding means, of a fluid pressure operated motor for moving said feeding means, a controlling valve for the fluid pressure therefor, and means for operating said valve by the movement or shifting of the feeding means.
7. In a shell loading machine, the combination with a shiftable feeder, of a fluid pressure operated motor for shifting said feeder, a hand-operable valve controlling the fluid pressure therefor, whereby the feeder may be made to move in one direction, and means for moving the valve by the movement of the feeder.
8. In a shell loading machine, the combination with a shell holder, of a feeder movable toward and away from the shell-holder, a fluid pressure operated motor for shifting said feeder, a controlling valve for the fluid pressure for said motor, and means operated by the feeder as it retreats due to the reactive pressure of the material being loaded into the shells which is adapted to cause operation of said controlling valve.
9. In a shell loading machine, the combination with an upright frame, of a carriage slidable up and down thereon, a hopper mounted on the carriage and provided with extrusion nipples, a cylinder on the carriage, a piston operating in the cylinder, a plunger connected to the piston and adapted to operate in the hopper, and means for raising and lowering the carriage.
10. In a shell loading machine, the combination with an upright frame, of a carriage slidable up and down on said frame, a hopper mounted on the carriage and provided with extrusion nipples, a cylinder mounted on the carriage, a piston operating in the cylinder, a plunger connected to the cylinder and adapted to operate in the hopper, a cross-head connected to the plunger stem and having parts slidable on the movable frame aforesaid.
11. In a shell loading machine, the combination with a hopper having an extrusion mouth, of an extruding or forcing device adapted to move in the hopper, fluid pressure operated means for shifting said extruding device, and fluid checks for controlling the movement of the extruding device to prevent such movement from being too abrupt.
12. In a shell loading machine, the combination with a shiftable carriage, of a hopper carried thereby having an extrusion mouth, an extruding device adapted to operate in the hopper, fluid pressure operated means adapted to shift the carriage to and fro, and a fluid check adapted to prevent too abrupt movement of the carriage.
13. In a shell loading machine, the combination with a feeder, of a piston and cylinder for operating the feeder, means for supplying compressed air to the cylinder on both sides of the piston, whereby it may be moved in either direction which includes a valve common to both of said air supplying means adapted when admitting air to one side of the piston to cause its exhaust from the other side thereof.
14. In a shell loading machine, the combination with a feeder, of a piston and cylinder for operating the feeder, means for supplying compressed air to the cylinder on both sides of the piston, whereby it may be moved in either direction which includes a valve common to both of said air supplying means adapted when admitting air to one side of the piston to cause its exhaust from the other side thereof, a fluid pressure motor for operating said valve, and a pilot valve controlling said fluid pressure motor.
15. In a shell loading machine, the combination with a feeder, of a piston and cylinder for operating the feeder, means for supplying compressed air to the cylinder on both sides of the piston, whereby it may be moved in either direction which includes a valve common to both of said air supplying means adapted when admitting air to one side of the piston to cause its exhaust from the other side thereof, a fluid pressure motor for operating said valve, a pilot valve controlling said fluid pressure motor, and means operated by the feeder when the shells have been loaded adapted to automatically operate the pilot valve.
16. In a shell loading machine, the combination with a feeder mounted for movement as an entirety, of an extruding device for the feeder which is movable independently of the bodily movement of the feeder, a piston and cylinder adapted for bodily shifting the feeder, another piston and cylinder adapted for operating the extruding device, and means for supplying fluid pressure to either side of the respective pistons aforesaid or for exhausting the pressure from either side of the respective pistons

aforesaid which includes a valve common to all of said supplying and exhausting means whereby fluid pressure may be supplied to the respective pistons or exhausted therefrom.

17. In a shell loading machine, the combination with a feeder mounted for movement as an entirety, of an extruding device for the feeder which is movable independently of the bodily movement of the feeder, a piston and cylinder adapted for bodily shifting the feeder, another piston and cylinder adapted for operating the extruding device, means for supplying fluid pressure to either side of the respective pistons aforesaid or for exhausting the pressure from either side of the respective pistons aforesaid, and means for controlling the supply and exhaust of the pressures aforesaid.
18. In a shell loading machine, the combination with a feeder mounted for movement as an entirety, of an extruding device for the feeder which is movable independently of the bodily movement of the feeder, a piston and cylinder adapted for bodily shifting the feeder, another piston and cylinder adapted for operating the extruding device, means for supplying fluid pressure to either side of the respective pistons aforesaid or for exhausting the pressure from either side of the respective pistons aforesaid which includes a valve common to all of said supplying and exhausting means whereby fluid pressure may be supplied to the respective pistons or exhausted therefrom, a fluid pressure operated device for moving the valve aforesaid, a pilot valve controlling said fluid pressure operated device, and means operated by the shifting of the feeder adapted for operating said pilot valve.
19. In a shell loading machine, the combination with a feeder, of a fluid pressure operated device for operating the feeder, and controlling means for the fluid pressure and exhaust adapted to reduce or cut down the fluid pressure utilized to start the feeding operation and to allow a quick and full application of the fluid pressure utilized to restore the feeder to inoperative position.
20. In a shell loading machine, the combination with a movable feeder, of a piston

and cylinder adapted for operating said feeder, pipes communicating with the cylinder on opposite sides of the piston, a controlling valve, and check valves arranged in the pipes so that a checked or slow and reduced fluid pressure is applied to the piston when utilized to start the feeder in operation and adapted to slowly let off or exhaust any opposing fluid pressure, on the one hand, and, on the other hand, to quickly supply fluid pressure to the piston and to quickly let off or exhaust any opposing fluid pressure when the controlling valve is arranged to admit pressure to return the feeder to normal position.

21. In a shell loading machine, the combination with a shiftable feeder, of a piston and cylinder for shifting said feeder to position it for loading the shells, a relief valve for the cylinder adapted to be set to operate at any predetermined pressure to thereby regulate the density of the material loaded into the shells, and a controlling valve for opening or cutting off communication between the relief valve and the cylinder, and means for automatically actuating said controlling valve.

22. In a shell loading machine, the combination with a bodily movable feeder, of a piston and cylinder for moving said feeder bodily, a piston and cylinder for operating the feeder independently of its movement bodily, means controlling the supply of fluid pressure to the respective cylinders, a relief valve for the cylinder that is adapted to bodily shift the feeder, said relief valve being adapted to be set to let off at any predetermined pressure, a controlling valve for opening or cutting off communication between the relief valve and its cylinder, and an operative connection between said relief valve and the bodily movable feeder, whereby the advance or retreat of the bodily movable feeder causes operation of said controlling valve.

In testimony whereof, I hereunto affix my signature in presence of two witnesses.

HERBERT TALLEY.
